UNITED STATES PATENT OFFICE.

JOSEF STEINGÄSSER AND EMIL GOTTESLEBEN, OF MAYENCE, GERMANY.

WOOD GRINDING AND POLISHING MACHINE.

1,075,515.

Specification of Letters Patent. Patented Oct. 14, 1913.

Application filed February 21, 1913. Serial No. 749,880.

To all whom it may concern:

Be it known that we, JOSEF STEINGÄSSER and EMIL GOTTESLEBEN, subjects of the Emperor of Germany, residing at Mayence, 5 Germany, have invented certain Improvements in Wood Grinding and Polishing Machines, of which the following is a specification.

The present invention relates to a wood 10 grinding and polishing machine of the kind in which the tool is held by a resiliently extensible and swingingly suspended driving shaft and adapted, while in motion, to adjust itself at various angles as determined 15 by the surface under treatment.

The invention consists in the various details of construction and combination of parts as hereinafter set forth and claimed, its object being to provide a simple and 20 easily operated machine whose revolving parts are, as far as practicable, covered up.

In the accompanying drawings the invention is illustrated, Figure 1 representing a side view of the machine, partly in section, 25 some of the elements being shown by broken lines, Fig. 2, a view of the upper part of the same, at right angles to Fig. 1, and Fig. 3, a plan of the tool, the left half being shown in section on the line A—A of Fig. 1, and the 30 other half in elevation.

The machine is composed of an electro- 35 motor *a* which is rigidly secured to a shaft 12 and suspended by means of the latter in a block 10, the latter being formed with an upwardly tapering slot 11 in which the shaft can move. The block 10 is itself pivoted to a carriage 9 which is guided by means of rollers along a supporting rail 16. The block 10 rocks in a plane which is 40 at right angles to the movement of the shaft 12 relative to the block. Owing to this arrangement the motor *a* is able to swing about the carriage 9 in all directions. It can also be transported by means of the 45 carriage along the rail 16. A plate 13, secured to the block 10, has a slot in which the shaft 12 is guided. A spring 15 encircles the shaft 12 and bears against the plate 13 and against an adjustable nut 14 on the shaft. This spring although it allows the shaft to rock relative to the block 50 10, tends to urge the carriage 9 in the same direction as the shaft is swung. It is not, therefore, necessary to swing the shaft to the whole extent allowed by the plate 13 for moving the carriage. A cord *b* or the like,

suspended within reach of the operator, is employed for the starting and stopping of the motor.

Adjoining the lower part of the motor 60 casing is a bearing *c* which holds the motor shaft *d*. Snugly fitted on and rigidly secured to the bearing *c* is a pipe *e* within which another pipe *f* is adapted to move rotatably as well as longitudinally. The 65 upper end of the pipe *f* holds a flanged socket *h* which guides the pipe within the pipe *e* and which slides on a square extension *g* of the motor shaft *e*. The rotary movement of the shafts *d* and *g* will therefore be transmitted to the pipe *f* the lower 70 end of which is guided in a socket *i* secured to the corresponding end of the pipe *e*. A shaft *k* is secured to the lower end of the pipe *f* so as to rotate with the latter. This 75 latter shaft is surrounded by a sleeve *p* which is supported by a collar and fitted with radiating arms *m* and *n* between which actuating handles *l* are held in a vertical position. A clamp *q* on the sleeve 80 *p* holds one end of a helical spring *s* the opposite end of which is connected to a clamp *r* secured to the pipe *e*. The sleeve *p* bears against the end of the pipe *f* and holds the latter normally, under the influence 85 of the spring *s* in its highest position. By means of the handles *l*, the pipe *f* can, while rotated by the motor, be drawn out of the pipe *e* in opposition to the spring *s*.

A spherical body *6* is screwed on the end 90 of the shaft *k* for the reception of the tool. The tool is in the present instance composed of a polishing disk *t* which is secured by means of curved blade springs *x* to a plate *w* so that it can adapt itself resiliently relative to the latter. The plate *w* is encircled by a ring *u* and carries in addition another, narrow ring *v* to which shells *7*, clasping the body *6* are secured. The shells *7* hold the tool connected to the body *6* and enable 100 it to turn about the latter, to a limited extent, in any desired vertical plane. The shells *7* are formed with vertical slots *8* in which are guided the heads of two diametrically opposite screws *17* fitted in the body 105 *6*. These screws, while allowing the tool to turn as previously noticed, compel the same to participate in the rotary movement of the body *6*.

The machine is manipulated by means of 110 the handles *l* and allows, as will be apparent from the foregoing, the tool to be moved

axially relative to the motor *a* and swingingly about the carriage *g*. The tool, moreover, is capable of adjusting itself about the body *b* relative to the surface under treatment.

For supplying polishing liquid to the disk *t*, bottles *o* are mounted on the arms *n*, as shown by broken lines in Fig. 1. Tubes *z* lead from the bottles *o* to a funnel *l* which 10 is secured to the body *b* and which communicates, through ducts *2*, with a central chamber *3* in said body. Another duct *4* leads from the chamber *3* through a nipple formed at the lower part of the body *b* and 15 delivers the liquid onto the disk *t* which admits the same through perforations *5* to the work piece. A flanged socket *y* is secured to the upper surface of the disk *t* so as to form a chamber in which to retain the polishing liquid within reach of the perforations *5*. The nipple of the body *b* projects 20 into the socket *y* which is accommodated in a central aperture in the plate *w*.

We claim:—

1. A wood grinding and polishing machine comprising in combination, an electromotor suspended by means of a universal link, a square-sectioned downward extension on the motor shaft, a pipe rigidly connected to the motor casing so as to inclose said extension, another pipe loosely guided within the rigid pipe and engaging the square extension of the motor shaft so as to be rotated by the latter while it allows of 25 simultaneous longitudinal movements, a shaft secured to the lower end of the inner pipe so as to project through the outer pipe, a sleeve rotatably held on said latter shaft, a spring acting on said sleeve and on the outer pipe for holding the inner pipe normally in its highest position, a tool held in the lower end of the latter shaft so as to allow of universal movement, and means connected to said sleeve for manipulating the 30 tool while in movement.

2. A wood grinding and polishing machine, comprising in combination, an electromotor suspended by means of a universal link, a square-sectioned downward extension

on the motor shaft, a pipe rigidly connected to the motor casing so as to inclose said extension, another pipe loosely guided within the rigid pipe and engaging the square extension of the motor shaft so as to be rotated by the latter while it allows of 50 longitudinal movements, a shaft connected to the lower end of the inner pipe, a spherical body secured to the end of said latter shaft, a shell held by said body so as to allow of universal movement, diametrically opposite screws connected to the body and guided in vertical slots in the shell so as to compel the latter to participate in the rotary movement of the body, a plate secured to said shell a polishing disk connected by means of springs to said plate and provided with perforations, means for feeding polishing liquid through the body to the disk, a socket connected to the upper surface of the disk so as to receive the liquid and confine the same to the perforated portion of the disk, means for holding the inner pipe normally entirely within the outer pipe, and means for manipulating the tool.

3. A wood grinding and polishing machine, comprising in combination, an electromotor having a longitudinally extensible shaft, a pipe rigidly connected to the motor casing so as to inclose said shaft, a tool connected to the lower end of the shaft so as to allow a universal movement, a rigid shaft connected to the motor casing opposite the rotatable shaft, a block having an upwardly tapering slot, said rigid shaft being pivoted to the block so as to move within the slot, a cage to which the block is pivoted so as to move in a plane at right angles to the movement of the rigid shaft, and a helical spring encircling the rigid shaft 85 and abutting against the block and against a nut on the shaft, substantially as and for the purpose set forth.

JOSEF STEINGÄSSER.
EMIL GOTTESLEBEN.
